CLAIM

The ornamental design for a footwear article, as shown and described.

DESCRIPTION

FIG. 1 is a left side view of a footwear article according to the present invention.

FIG. 2 is a right side view of the footwear article of FIG. 1.

FIG. 3 is a top view of the footwear article of FIG. 1.

FIG. 4 is a bottom view of the footwear article of FIG. 1.

FIG. 5 is a front view of the footwear article of FIG. 1; and,

FIG. 6 is a back view of the footwear article of FIG. 1.

The broken lines in FIGS. 1-6 illustrate portions of the footwear article that form no part of the claimed design. In FIGS. 1-3 and 5-6, the oblique line shading on side, front, and back portions of the shoe forming a lower band represents translucent surfaces.

Further, in FIGS. 1-3 and 5-6, the irregular polygonal patterns on the upper side and top portions of the shoe represent fabric material. However, the patterns do not form part of the claimed design.

Further, in FIGS. 1-2 and 6, the oblong dashed lines shown on the side and back portions of the shoe do not form part of the claimed design.

Further, the stitch lines along the lace edge shown in FIGS. 1-3 and 5 do not form part of the claimed design.
